UNITED STATES PATENT OFFICE.

ROBERT LEE CONDRA, OF SAN ANTONIO, TEXAS.

LIQUID-FUEL HEATER.

Application filed August 12, 1924. Serial No. 731,648.

To all whom it may concern:

Be it known that I, ROBERT L. CONDRA, a citizen of the United States, and resident of San Antonio, in the county of Bexar and State of Texas, have invented a new and Improved Liquid-Fuel Heater, of which the following is a full, clear, and exact description:

This invention has relation to liquid fuel heating devices and has particular reference to an improvement in fuel oil heaters which are especially designed for use in connection with steam, hot water or hot air furnaces.

One of the principal objects of the present invention, is to provide a means for thoroughly gasifying the fuel oil, prior to the ignition of the same, whereby the maximum heat may be derived therefrom.

As a further object the invention contemplates in a fuel oil heater, a means for effectually mixing the air and gas to promote a more thorough combustion thereof, which means also serves to effectually radiate the heat and distribute the same throughout the fire box in which the device is located.

As a still further object the invention comprehends an improvement in fuel oil heaters which is comparatively simple in its construction, inexpensive to manufacture and install and which is thoroughly reliable and highly efficient in its purpose.

With the above recited and other objects in view, the invention resides in the novel construction set forth in the following specification, particularly pointed out in the appended claims and illustrated in the accompanying drawings, it being understood that the right is reserved to embodiments other than those actually illustrated herein, to the full extent indicated by the general meaning of the terms in which the claims are expressed.

In the drawings—

Figure 1 is a perspective view of the device;

Fig. 1^a is a perspective view of the heating cup used for starting the burner;

Fig. 2 is a transverse sectional view through the heating device taken approximately on the line 2—2 in Fig. 1; and

Fig. 3 is a horizontal sectional view taken approximately on the line 3—3 in Fig. 2.

Referring to the drawings by characters of reference 10 designates a supporting base

for the device which is provided at one end with an upstanding standard 11 which supports at its upper end the bight portion 12 of the fuel gasifying or generating element 13 designated generally at 13 which element is of substantially U-shaped formation including parallel pipes 14 and 15 joined by the bight portion or return bend 12. The pipe 15 is connected to a supply conduit 16 at its free end by an increaser union 17 and the supply conduit 16 has interposed therein a controlling valve 18 the manipulating handle 19 of which is provided with an indicating pointer 20 which may cooperate with a suitable dial not shown. The other leg or pipe 14 of the gasifying or generating element 13 is provided with a depending pipe or conduit 21 connected thereto by an elbow 22 and said pipe 21 is connected at its lower end by an elbow 23 with the base 10 by means of attaching ears 24 and bolts 25 which extend through the ears and base 10. From the elbow 23 a pipe or conduit 26 leads horizontally to the lower end of a nozzle 27 which is disposed centrally below the gasifying or generating member 13.

A super-posed air and gas mixing and heat radiating element designated generally by the reference character 28 is supported 85 from the gasifying or generating element 13 and the said element 28 consists of a rectangular shaped element 29 having a double arch-shaped bottom 30 provided with a central depending stem 31 which is gripped by 90 the parallel pipes 14 and 15 of the gasifying or generating element 13. The side walls of the rectangular shaped element 29 are provided with a plurality of perforations 32 both above and below the depending arch 95 shaped bottom 30. An air supply pipe 33 having a perforated lower end 34 leads centrally into the element 29 and rests upon the bottom 30. The leads or pipes 14 and 15 are disposed immediately below the convex undersides defined by the double-arch shaped bottom 30.

In starting the device, a heating cup or pan 35 is employed which is provided with a handle 36. Kerosene is poured into the heating cup or pan 35 and the same is arranged under the generating element 13 after which the kerosene is lighted and a sufficient amount of fuel oil is permitted to enter the generating element. The heat from the 105 heating cup or pan 35 will initially heat the 110 generating or gasifying element 13 until the

gas starts to feed through the nozzle 27. The gas from the nozzle 27 will then be ignited and the valve 18 will be controlled by the manipulating handle 19 to permit the 5 fuel oil to be fed to the generating element 13 to the supply pipe 16 where it will be continuously gasified or generated into a gas as it feeds through the pipes 14 and 15, and the pipes 21 and 26 to the nozzle 27. The 10 jet or flame from the nozzle 27 will be deflected or spread laterally by a spreader element 37 adjustably supported from the depending stem 31. The flame will thus be directed upwardly and outwardly around 15 the air and gas mixing and heat radiating element 28, a part of the heat being deflected inwardly and around the pipes 14 and 15 of the generating element, by the convex undersides of the depending arch shaped bottom 20 30. At the same time the cold air descending through the pipe 33 will be deflected laterally through the perforations 34 and the perforations 32 to thoroughly mix with the gas and flame whereby to promote a thorough and complete combustion. It is of course understood that after the burner is started, the heating pan or cup 35 is removed. The perforated or foraminated 25 walls of the rectangular element 29 serve to spread or radiate the heat to uniformly distribute the same through the fire box of the furnace and prevent the draft from drawing the same through the chimney before it has had sufficient time to thoroughly function 30 to heat the furnace fire box.

I claim:

1. In a liquid fuel heating device, a fuel 40 gasifying element respectively connected at its opposite ends with a fuel supply and a subter-posed burner nozzle, and an air and gas mixing and heat radiating member supported in super-posed relation to the gasifying element, said member comprising a rectangular foraminated body having a double 45 arch shaped bottom.

2. In a liquid fuel heating device, a fuel 50 gasifying element respectively connected at its opposite ends with a fuel supply and a subter-posed burner nozzle, and an air and gas mixing and heat radiating member supported in super-posed relation to the gasifying element, said member comprising a rectangular foraminated body having a double arch shaped bottom and a spreader element 55 depending from the bottom of said member and overlying the nozzle, to cause the flame or jet therefrom to encompass the air and gas mixing and heat radiating member.

3. In a liquid fuel heating device, a fuel 60 gasifying element respectively connected at its opposite ends with a fuel supply and a subter-posed burner nozzle, and an air and gas mixing and heat radiating member supported in super-posed relation to the gasifying element, said member comprising a rec-

tangular foraminated body having a double arch shaped bottom and a spreader element depending from the bottom of said member and overlying the nozzle, to cause the flame or jet therefrom to encompass the air and gas mixing and heat radiating member the convex under surfaces defined by the double arch shaped bottom, serving to direct the heat circumferentially about the peripheries of the leads of the gasifying element. 70

4. A liquid fuel heating device including a fuel gasifying element comprising a substantially U-shaped pipe member having horizontally disposed parallel leads connected at one end by a bight portion, the free end of one of the said leads having communication with a source of fuel supply, the free end of the other lead having communication with a subter-posed burner nozzle, an air and gas mixing and heat radiating member supported in super-posed relation to the gasifying element, said member comprising a rectangular foraminous body having a double arch shaped bottom, a spreader element depending from the bottom of said latter member and overlying the nozzle to cause the flame or jet therefrom to encompass said member and the convex under surfaces defined by the depending arch shaped bottom serving to direct a portion of the heat circumferentially about the peripheries of the leads of the gasifying element whereby to thoroughly heat the same to generate the gas from the fuel flowing therethrough. 80

5. A liquid fuel heating device including a fuel gasifying element comprising a substantially U-shaped pipe member having horizontally disposed parallel leads connected at one end by a bight portion, the free end of one of the said leads having communication with a source of fuel supply, the free end of the other lead having communication with a subter-posed burner nozzle, an air and gas mixing and heat radiating member supported in super-posed relation to the gasifying element, said member comprising a rectangular foraminous body having a double arch shaped bottom, a spreader element depending from the bottom of said latter member and overlying the nozzle to cause the flame or jet therefrom to encompass said member and the convex under surfaces defined by the double arch shaped bottom serving to direct a portion of the heat circumferentially about the peripheries of the leads of the gasifying element whereby to thoroughly heat the same to generate the gas from the fuel flowing therethrough and means for controlling and regulating the liquid fuel supply. 90

6. A liquid fuel heating device including a fuel gasifying element comprising a substantially U-shaped pipe member having

horizontally disposed parallel leads connected at one end by a bight portion, the free end of one of the said leads having communication with a source of fuel supply, the free end of the other lead having communication with a subter-posed burner nozzle, an air and gas mixing and heat radiating member supported in super-posed relation to the gasifying element, said member comprising a rectangular foraminous body having a double arch shaped bottom, a spreader element depending from the bottom of said latter member and overlying the nozzle to cause the flame or jet therefrom to encompass said member and the convex under surfaces defined by the double arch shaped bottom serving to direct a portion of the heat circumferentially about the peripheries of the leads of the gasifying element whereby to thoroughly heat the same to generate the gas from the fuel flowing therethrough and means for controlling and regulating the liquid fuel supply, said latter means consisting of a valve, an operating element therefor and indicating means carried by the operating element and adapted to cooperate with a dial.

5 10 15 20 25

a fuel gasifying element comprising a substantially U-shaped pipe member having horizontally disposed parallel leads connected at one end by a bight portion, the free end of one of said leads having communication with a source of fuel supply, the free end of the other lead having communication with a subter-posed burner nozzle, an air and gas mixing and heat radiating member supported in super-posed relation to the gasifying element, said member comprising a rectangular foraminous body having a double arch shaped bottom, a spreader element depending from the bottom of said latter member and overlying the nozzle to cause the flame or jet therefrom to encompass said member and the convex under surfaces defined by the double arch shaped bottom serving to direct a portion of the heat circumferentially about the peripheries of the leads of the gasifying element whereby to thoroughly heat the same to generate the gas from the fuel flowing therethrough and means for initially heating the gasifying element comprising a fuel pan insertable beneath the gasifying element.
